UNITED STATES PATENT OFFICE.

JULIUS J. GRUENFELD, JR., OF CHICAGO, ILLINOIS.

SOFA-BED.

1,352,806.

Specification of Letters Patent. Patented Sept. 14, 1920.

Application filed September 13, 1916. Serial No. 119,817.

To all whom it may concern:

Be it known that I, JULIUS J. GRUENFELD, Jr., a citizen of the United States, and a resident of Chicago, in the county of Cook and State of Illinois, have invented certain new and useful Improvements in Sofa-Beds, of which the following is a full, clear, and exact description.

The invention relates to sofa beds.

One object of the invention is to provide improved connecting devices between a sofa frame and a bed composed of foldably connected sections, whereby, in the course of swinging the bed from a closed to an open position, it will move about different fulcrums in succession as distinguished from a combined sliding and pivotal connection or a differential link connection.

By providing connections by which the bed is caused to swing in succession about differently disposed fulcrum points, the bed will swing in such a manner as to render available some of the space to the rear of and below the bed for storage of bedding, etc., without enlarging the sofa frame.

A further object of the invention is to provide improved connecting-devices between the frame and the bed, which are simple in construction, may be easily operated and can be produced at a low cost. Other objects of the invention will appear from the detail description.

The invention consists in the several novel features hereinafter set forth and more particularly defined by claims at the conclusion hereof.

In the drawings: Figure 1 is a vertical transverse section of a sofa bed, embodying the invention, the bed being shown closed. Fig. 2 is a similar view, showing the bed open. Fig. 3 is a section taken on line 3—3 of Fig. 1. Fig. 4 is a horizontal section taken on line 4—4 of Fig. 1. Fig. 5 is a face view of one of the slotted plates secured to the stationary sofa frame. Fig. 6 is an end view of the stud-plate fixed to the bed frame. Figs. 7, 8, and 9 are detail views of the stud plate and slotted fulcrum plate showing them in the positions assumed when the bed is closed, when it has been opened half way and in open position. Fig. 10 is a transverse section of a modification sofa bed, showing the invention applied to a five-section folding bed, the bed being

shown open. Fig. 11 is a similar view of the same showing the bed closed.

The sofa bed comprises essentially a sofa frame which may be of any suitable construction or design and a bed formed of foldably connected sections and movably mounted in the frame so that it can be spread in open position or folded under the seat. The sofa frame comprises sides 14 which are suitably cross-connected and secured together in spaced relation by bars 15 between which the back-rest 16 is disposed. In the form of the invention illustrated in Figs. 1 and 2, the bed comprises a section 17, a section 19 and an intermediate section 18. It will be understood by those skilled in the art that a spring-bed bottom (not shown) is connected to the bed sections to continuously support the mattress. The section 17 comprises side-bars 17^a and an end bar 17^b. The section 19 comprises side bars 19^a and a cross-bar 19^b. Usually all of these bars of the bed sections are of angle iron. The section 17 is rigidly secured to a seat frame 20 and a sofa-seat 21 is built upon said frame. The side bars of section 18 are 80 pivotally connected to the section 19 and the section 17 is pivotally connected to the side bars of the intermediate section 18. When the bed is closed, the sofa seat will be upon the top of the seat frame 20 and 85 the section will be inverted adjacent the underside of the seat. Intermediate section 18 will extend downwardly from the section adjacent the front of the seat and the section 17 will extend rearwardly from the 90 lower end of the intermediate section. Latches 36 hinged to the side bars of the section 17 are adapted to be swung into position to hold the section 19 so that a mattress will be held between the bed 95 sections when the sofa is closed. The front board 22 is hinged, as at 23, to the seat frame to conceal the bed sections and mattress when the sofa is closed.

A device for movably connecting the seat frame and bed to the sofa frame is provided between each end of the sofa frame and the ends of the seat respectively. Each of these connecting devices comprises a pair of studs 24, 25, riveted or otherwise suitably fixed to a plate 26 which is secured by screws 26' to the seat frame 20 and a plate 27 secured to one of the sofa frame sides 14.

by screws 28. A spacer plate 29 is interposed between each fulcrum plate and one side 14 of the sofa frame, and has slots 34 therein to provide clearance for the heads 5 24' and 25' of the studs 24 and 25. Each plate 27 is formed with intersecting arcuate slots 30 and 31, in the lower ends of which studs 24 and 25 are fulcrumed or held in alternating succession. Each of the slots 10 30 and 31 is substantially quadrantal so that each stud 24, 25 acts as a fulcrum, for about 90° of movement and collectively the studs act as fulcra for about 180° of movement. The studs at the opposite ends of the seat 15 frame are coaxial and the slots in the plates 27 are correspondingly disposed so that the bed and seat will simultaneously swing on corresponding studs. For assembling the stud plates and the slotted plates, openings 20 32 and 33 connecting with slots 30 and 31 respectively are provided to permit the heads of the studs on the plate 26 to be passed through the slotted plates until the reduced portions of the studs pass trans- 25 versely into position to slip into the slots 30 and 31. These openings 32 and 33 are disposed where both stud heads will not pass into registry with them during the opening or closing of the bed.

30 When the bed is closed and the seat is in operative position, studs 25 will bear in the lower ends of the slots 31 and studs 24 will be disposed adjacent the upper ends of the slots 30 (Fig. 7). When the seat and bed 35 are turned over to give access to the bed, studs 25, bearing in the lower ends of slots 31, will act as a fixed pivot or fulcrum for the seat and bed, while the studs 24 will move forwardly and downwardly in arcuate slots 40 30 until they encounter the lower ends of said slots (Fig. 8). When the seat and bed are approximately in vertical position, further forward movement thereof will cause studs 24 to act as a fulcrum and studs 25 45 will travel upwardly and forwardly in slots 31 until they engage the upper end of said slots, whereupon the seat will be locked against further forward and downward movement (Fig. 9).

50 A characteristic of this construction is that the connections result in pivotal movement about substantially fixed, differently disposed pivots in succession. The seat will swing about a substantially fixed fulcrum 55 which is advantageously disposed for the initial opening swing of the seat and bed, until the movement of the other stud is arrested, whereupon the stud which first acted as a pivot will be caused to swing around 60 the other stud as a fulcrum which, at that time, is advantageously disposed to give the desired direction of travel to the seat and bed during the latter portion of its movement. These devices further exemplify 65 stud-and-slot connections between the fold-

able bed and the frame by which the studs become active in alternating succession and in which the seat frame is successively pivoted about fixed fulcra. These stud-and-slot connections are simple in construction 70 and render shifting of the seat comparatively easy, because sliding friction is eliminated. Another attribute of these devices is that when the seat is closed or in operative position, the fulcrum about which the initial movement of the seat occurs, is disposed so that the rear end of the seat will swing upwardly and forwardly, and so that the rear end of the seat which is in close proximity to the back, will readily swing 80 away from and clear the back-rest. After the pivotal movement about the rearwardly disposed fulcrum has been completed, the other stud then in a forwardly disposed position becomes active and the seat moves 85 downwardly and forwardly to an inverted position where the bed sections will be exposed so they can be readily manipulated to form a bed.

A box 37 for the pillows and other bedding, if desired, is provided in the lower rear portion of the seat frame and extends longitudinally between the sides thereof. The front 37' of this box is inclined so that the section 19 will clear it during the initial 95 upward movement of the seat in opening the sofa.

Counter-balance springs 38, one at each end of the seat, have their front lower ends connected to the front board 22 and their rear ends connected to links 39 which are secured to the sofa frame, at 40. These springs aid in lifting and tilting the seat and bed during the initial upward movement thereof in opening the sofa. Springs 100 38 and links 39 are disposed so that the springs will be inactive after the seat has passed approximately to a vertical position and during the time when it is being lowered from vertical to its forwardly extending position. When the seat is in operative position, the seat-frame 20 rests upon lugs 41 secured to the frame-sides 14. Springs 42 are connected to the front board 22 and to the side-bars of section 19 to hold the 115 front board in substantially horizontal position, as shown in Fig. 2, when the bed is open.

The operation of the sofa bed will be as follows: When the sofa is closed, the parts 120 will be in position shown in Fig. 1. When the sofa is to be used as a bed, the seat will be turned over, the operator grasping the usual handle 44 secured to the back of the seat and pulling it upwardly and forwardly. Springs 38 will materially aid the operator, particularly during the initial movement, at which time, the major portion of the weight of the seat and bed will be back of the fulcrum stud 25 on which the seat is be- 130

ing swung. During the first 90° of the movement of the seat, the latter will pivot on the fulcrum studs 25 which are disposed comparatively low with respect to the seat-frame so that the rear portion of the seat will swing upwardly and forwardly and clear the back, and studs 24 will pass downwardly and forwardly in slots 30. When the seat has reached approximately an upper right position, studs 24 will seat in the lower end of slot 30. During further forward pull upon the seat, the latter will pivot on studs 24 and studs 25 will swing upwardly in slots 31 until they reach the upper front ends of said slots, whereupon the further movement of the seat will be arrested. During this forward movement of the seat, the front board 22 will be shifted with the seat. When the seat has been overturned, the storage compartment is readily accessible by lifting section 19, for removal or replacement of extra bed clothes. When the seat has been inverted, the bed-sections 18 and 19 will be swung rearwardly into the position shown in Fig. 2 and then the bed will be in open position, all of the sections being alined to form a bed bottom, and front board 22 will be raised into horizontal position shown in said figure and held suspended there by springs 42.

Legs 46 are pivotally connected to bed-section 17 and are adapted to be swung into position to support the front end of said section when the bed is open, as shown in Fig. 2.

To close the bed, sections 18 and 19 are swung into position indicated by dotted lines in Fig. 2 and are secured together in such position by latch 36. It will be understood that the spring-bed bottom connected to these sections and the mattress thereon may be folded with the sections. The seat with the bed sections connected thereto will then be swung backwardly and upwardly, pivoting on studs 24 while the studs 25 move downwardly and rearwardly toward and into the lower ends of slots 31. As the seat passes the vertical position, studs 25 will seat in the lower ends of slots 31 and thereafter will act as a fulcrum during the downward and rearward movement while studs 24 move upwardly and rearwardly in slots 30 until the seat is restored to the position shown in Fig. 1.

Figs. 10 and 11 illustrate the invention applied to a five-section bed comprising a medial section 50 secured to the seat frame 20, a short section 51 pivoted to section 50, at 52, a short section 53 pivoted to section 50, at 54, a head-section 55 pivoted to section 51, at 56, and a foot-section 57 pivoted to section 53, at 58. The pivotal connections between the sofa frame and the seat frame are precisely the same as those described in connection with the form of the

invention shown in Figs. 1 and 2. A storage compartment 59 is disposed to the rear of and below the seat frame and is provided with a front 60 which is hinged as at 61 to the sofa-frame to provide access to the compartment. When the bed is closed, the sections will assume the position shown in Fig. 11 and when open, the position shown in Fig. 10. Legs 62 are pivoted to the rear cross-bar of the seat to support the latter when the bed is open and legs 63 are pivoted to the front of the foot section 57 to support it when the bed is open. The storage space 60 serves to hold pillows and other bedding desired when the bed is folded up.

The invention exemplifies a sofa bed, in which pivotal stud-and-slot connections are employed between the seat and the sofa frame, in which the seat will move pivotally around different fulcrum points in succession, so that the friction resulting from sliding joints is eliminated, and in which the fulcrum points are advantageously disposed so that the bed sections will clear the storage space in swinging so that the seat and bed sections may be shifted with ease.

The invention is not to be understood as restricted to the details set forth, since these may be modified within the scope of the appended claims, without departing from the spirit and scope of the invention.

Having thus described the invention, what I claim as new and desire to secure by Letters Patent, is:

1. In a sofa bed, the combination of a sofa frame, a bed comprising foldably connected sections and connections between the sides of the bed and the frame respectively, each comprising a plurality of pivots and means for causing them to be successively and alternately held to successively act as stationary fulcra about which the bed swings, the corresponding pivots of the connections being coaxially disposed to cause both ends of the bed to successively swing about differently disposed stationary fulcra.

2. In a sofa bed, the combination of a sofa frame, a bed comprising foldably connected sections and connections between the sides of the bed and the frame respectively, each comprising a plurality of pivots and means for causing them to be successively and alternately held to successively act as stationary fulcra about which the bed swings, the corresponding pivots of the connections being coaxially disposed to cause both ends of the bed to successively swing about differently disposed stationary fulcra, said pivots being movable vertically to alternately bring one of them above the other.

3. In a sofa bed, the combination of a sofa frame, a seat frame, pivotal connections between the sofa and seat frames, a bed comprising foldably connected sections, supported by the seat frame, a front board

hinged to the seat frame so it will underlie a portion of the bed when the seat-frame is inverted, and a spring connection between the bed and the front board to govern the 5 position of the front-board with respect to the folding sections of the bed-frame.

4. In a sofa bed, the combination of a sofa frame, a seat frame, pivotal connections between the sofa and seat frames, a bed com-

prising foldably connected sections, supported by the seat frame, a front board hinged to the seat frame so it will underlie a portion of the bed when the seat-frame is inverted, and a spring connection between the bed and the front board to govern the 15 position of the front-board with respect to the folding sections of the bed-frame.

JULIUS J. GRUENFELD, JR.
